UNITED STATES PATENT OFFICE.

EDWARD S. DOTTER, OF CASTLE CREEK, NEW YORK.

EDGE-INKING MACHINE.

Application filed May 5, 1922. Serial No. 558,790.

To all whom it may concern:

Be it known that I, EDWARD S. DOTTER, a citizen of the United States, residing at Castle Creek, in the county of Broome and

5 State of New York, have invented certain new and useful Improvements in Edge-Inking Machines; and I hereby declare that the following is a full, clear, and exact description thereof, reference being had to the accompanying drawings, which form part of

10 this specification.

This invention is a novel improvement in edge inking rolls for applying ink to the edges of the soles, the shanks, and the heels, 15 of shoes.

The accompanying drawings show several inking rolls constructed in accordance with the invention, which will be herein-after described with reference thereto, and 20 the essentials of the invention and the novel features of construction and the novel combinations of parts for which protection is desired are set forth in the claims.

In the said drawings:

25 Fig. 1 is an enlarged face view of one of the inking rolls especially designed for applying ink to the edge only of soles.

Fig. 2 is a sectional view of the inking roll shown in Fig. 1.

30 Fig. 3 is a view, similar to Fig. 2, of a roll for applying ink to the shanks of shoes.

Fig. 4 is a face view of a roll for applying ink to the edge and upper stitched part of a shoe sole.

35 Fig. 5 is a part side and part sectional view of the roll shown in Fig. 4.

Fig. 6 is a part side and part sectional view of a roll for inking the heels of shoes.

40 Each inking roll is preferably formed of a hub or body 12^a which may be fastened to a shaft in any suitable manner so as to rotate therewith as by a set screw, and which has a radially disposed circumferential flange 12^a projecting beyond the periphery 45 of the body; and surrounding one end of the body, and abutting against the flange is an annular felt rim 12^b which presses against the flange 12 and is confined in position on the body by an outer metal guide disk 12^c which may be fastened to the body opposite flange 12 by screws 12^d or any suitable means. The guide disk 12^c is slightly larger in diameter than the felt rim, and is rounded on the side next to the felt rim and serves 50 as a guide to assist the operator in positioning the edge of the shoe sole (or the

shoe shank) (or the heel) against the periphery of the felt rim. The felt rim is supplied with ink by any suitable means or manner.

60 The form of ink roll shown in Figs. 1 and 3 is adapted to apply the ink only to the outer edge of the sole without staining the upper edge or stitches thereof. The edge of the guide disk 12^c prevents ink getting onto 65 the stitches.

The roll shown in Fig. 3 is constructed like that shown in Figs. 3 and 4 except that the felt rim 12^b has its periphery concaved as shown at 12^e, so that the felt will properly ink the beveled or rounded edge of the shank of the sole. The disk 12^c prevents ink or blacking flowing beyond the edge of the sole.

70 When it is desired to have the stitches on the upper edge of the sole inked, as well as the outer edge of the sole, the roll shown in Figs. 4 and 5 is employed. In this construction of the roll the hub or the body is elongated and an annular or disk brush 13 is 80 placed on the hub exterior to the felt rim the periphery of the brush projecting beyond the felt rim; a metal disk 13^a is preferably interposed between the brush and the felt rim 12^b. The brush 13 is held in 85 position and clamped against the rim and the latter against the body 12, by screws 12^d. The brush 13 will apply ink to the upper stitched edge of the sole at the same time that the felt rim 12^b applies ink to the outer 90 edge of the sole.

95 The heel inking roll shown in Fig. 6 is constructed like the roll shown in Figs. 1 and 2, only the felt rim is made wider to properly apply ink to the heel. All the rolls are similar in construction and differ only as necessary to suit the different purposes for which they are intended.

The felt inking rolls, as described, are much superior to brushes for inking the 100 edges of soles and heels of shoes. Applicant's disks roll the ink on the edges of the soles or heels. With brushes the ink cannot possibly be rolled on, and if the brushes are rotated at all quickly they will throw 105 the ink in various directions and spatter it on the uppers and upper edges of the soles; whereas applicant's felt rolls will roll the ink on, and do not spatter the ink.

110 It will be seen that in this invention the guides rotate with the ink applying rollers and are not stationary, as are the guides in

edge inking machines as commonly constructed. In practice the soles and heels of the shoes are moved slowly by the ink rolls, which are rotated just fast enough to enable the ink to be rolled on the edges of the soles and heels by the felt rims rather than brush or rub the ink thereon.

What I claim is:

1. An edge inking roll comprising an approximately circular body, an annular inking rim abutting against the body, a disk holding said rim in place, and a brush interposed between the disk and rim and projecting beyond the periphery of the rim, substantially as described.

2. An edge inking roll comprising an approximately circular body having a hub, an annular felt rim mounted on such hub and abutting against the body, a disk attached to the hub for holding said rim in place, a brush interposed between the disk and rim and projecting beyond the periphery of the rim, and a metal plate interposed between the brush and rim, substantially as described.

3. An edge inking roll comprising an approximately circular body having a hub, an

annular felt rim mounted on such hub and abutting against the body, a metal disk projecting beyond the periphery of the felt rim and serving as a guide, means for fastening the disk to the body, a brush interposed between the disk and rim and projecting beyond the periphery of the rim, and a metal plate interposed between the brush and felt rim.

4. An edge inking roll comprising a body having a hub and a flange; an annular non-expansible felt rim directly mounted on such hub and abutting against the flange, said felt rim being of greater diameter than said flange; a removable metal disk on the hub for holding said felt body in place, the disk being of greater diameter than said body and the part of the disk projecting beyond the adjacent periphery of the felt rim serving as a guide to assist the operator in positioning the edge of the shoe against the felt rim, and means for attaching the disk to the body.

In testimony that I claim the foregoing as my own, I affix my signature.

EDWARD S. DOTTER.
